UNITED STATES PATENT OFFICE.

LEMUEL J. CAYWOOD, OF MONTEREY PARK, CALIFORNIA.

BAG RACK.

Application filed March 10, 1924. Serial No. 698,042.

To all whom it may concern:

Be it known that I, LEMUEL J. CAYWOOD, a citizen of the United States, residing at Monterey Park, in the county of Los Angeles and State of California, have invented new and useful Improvements in Bag Racks, of which the following is a specification.

This invention relates to a rack for holding and printing paper bags and it has as one of its objects the provision of a rack into which a stack of bags may be placed, the rack automatically shuffling the bags to accomplish a positioning of the bags with respect to each other so that a predetermined number of bags may readily be withdrawn from the rack.

Another object of this invention is the provision of means for printing a bag as it is withdrawn from a rack of this invention.

With the foregoing objects in view, together with such other objects and advantages as may subsequently appear, my invention resides in the construction and arrangement of parts hereinafter described and claimed and illustrated in the accompanying drawings, in which:

Figure 1 is an elevational view of a rack embodying my invention and showing paper bags in the rack,

Fig. 2 is a side view of the rack,

Fig. 3 is a section taken on the line 3—3 of Fig. 2, and

Fig. 4 is an end view of a printing roller and inking pad employed in my device.

Referring to the drawings for a more detailed description thereof, the numeral 7 indicates the base of the rack, which may rest on a counter 7^a. To the base 7 is secured on one side and at the ends thereof uprights 8 and 9 respectively, and at its middle portion an upright 10^a and to the other side of the member 7, opposite the upright 10^a, is secured an upright 10. A member 11 is spaced above the base 7 and is similarly secured to the uprights 8, 9, 10 and 10^a.

A horizontal bar 12 has pointed ends 13 which penetrate the member 11 from the underside thereof. The bar 12 has side portions 12^a which project in front of the uprights 8 and 9 and thus serve to space the front portion of the bar 12 from the uprights 8 and 9.

Associated with the central portion of the bar 12 is a member 15 secured thereto by

having its upper end portion bent around the bar 12. The member 15 is bent back on itself at a point 16 forming a space 17 into which is tightly fitted a tongue 18 of a spring 19, the lower end portion of which is secured by fastening means 20 to a frame 21, in which are rotatably mounted a printing cylinder 22 and a cylindrical inking pad 23, the inking pad and the printing cylinder being in contact with each other. The lower end of the member 15 is provided with a point 15^a, which, by penetrating the base 7, serves to keep the member 15 in position. The inner side of the lower portion of the member 15 is provided with serrations or teeth 25, which, by reason of the inclined position given the lower portion of the member 15, serve to shuffle, or hold in graduated position, a bunch of paper bags 27, which are held between the upright 10^a and the horizontal bar 12. It will be seen that the top of the outermost bag is highest and the tops of the inner bags are successively in lower positions. This arrangement facilitates the withdrawal of a bag or any desired number of bags from the rack.

When the bags 27 are in position, the printing cylinder 22 is kept by the tension of the spring 19 against the outermost bag and when this bag is withdrawn the printing cylinder, which contains the matter to be printed, rotates against the bag and prints thereon, the printing cylinder deriving ink from the cylindrical inking pad with which it is in contact, and against which it rotates; the cylindrical inking pad also being rotated. This feature of the invention provides for a simple, economical and efficient means of advertising.

Opposite the rack described above may be placed a rack 30 of the same construction but adapted to hold bags of a different size than the bags 27.

A rack formed of a bar, plate, or the like, such as 15, with the serrations or teeth 25, may be used for other purposes than stacking paper bags. It may usefully be employed for other paper articles such as newspapers or the like which it is desired to shuffle or place in the rack in echelon so that one at a time may be readily withdrawn.

While I have herein described one form

of my invention, modifications thereof may be devised without departing from the spirit thereof, and it is to be understood that such modifications come within the scope of this 5 invention.

What is claimed is:

1. A bag rack comprising in combination a rigid backing member forming a backing for the bags, a front retaining member having serrations at its inner side, adapted to shuffle or arrange bags in echelon, a closed connection between the lower end of the front retaining member and the backing member and a spaced open end at the upper 10 part of the backing member and the front retaining member whereby bags may only be removed through the upper open end.

2. A bag rack comprising in combination a frame composed of a rigid substantially 20 vertical backing member, a front inclined member secured thereto at its lower end and forming a lower closure and having a series of serrations on its inner faces adapted to shuffle or arrange bags in echelon and a brace 25 connecting the front inclined member at its upper end to the backing member, said brace holding the inclined member spaced from the backing member and forming an opening for the insertion and removal of bags.

3. A bag rack comprising in combination an upright board forming a backing for bags, an inclined bar or the like having a prong 30 at its lower end and driven into the board and forming a closure between the board and the inclined bar, a series of serrations on the inner edge of the bar adapted to shuffle or arrange bags in echelon, the upper end of the bar having a cross piece spaced from the board adapted to hold bags and allow for 35 the insertion and removal of the bags only from the upper end of the inclined bar.

4. A bag rack as claimed in claim 3, in which the cross piece has arms on each end with means thereon for attachment to the 40 board.

5. A bag rack comprising in combination an upright board forming a backing for bags, an inclined bar or the like having a series of teeth or serrations at its lower inside face adapted to shuffle or arrange the bags between the board and the bar in echelon, means to secure the inclined bar to the board at its lower end and form a permanent closure, a rod attached to the upper 50 end of the inclined bar and extending cross-wise thereof parallel to the face of the board and having arms extending towards the board and means to secure said arms to the board, thereby spacing the upper end of the 55 inclined bar from the board and forming an opening for the insertion, the retaining in position and the removal of the bag.

6. A bag rack as claimed in claim 5, in which the inclined bar is secured to the board at its lower end by a prong and in

which the arms have a point forming a prong.

7. A bag rack comprising in combination a backing member, a front inclined member adapted to arrange a series of bags held in the rack in echelon, and a printing device held in the rack and pressing against the outermost bag to print each bag in succession as it is withdrawn through the widest part 70 of the rack.

8. A bag rack comprising in combination an upright support forming a backing for the bags, an inclined bar or the like having a series of serrations on its inner edge adapted to stack the bags in echelon, a printing roller supported in the rack and bearing against the outermost bag, means to ink the printing roller, and means to press the printing roller against each successive bag 80 as the outermost bag is withdrawn after 85 printing.

9. A bag rack comprising in combination an upright backing member, a front inclined bar or the like having a series of serrations 90 on its inner surface, a rod at the top of the rack engaging the backing member and the front bar, a printing roller supported by a spring from the inclined bar, and an inking device therefor, said printing roller being situated within the rack and adapted to press against the outside bag and thereby print each bag in succession as it is withdrawn from the rack.

10. A bag rack comprising means for shuffling a plurality of bags as the latter are 100 inserted into the rack, said shuffling means comprising a series of serrations, and means for printing on the outermost bag as it is withdrawn from the rack, said printing means comprising a roller, a tensioned spring for pressing the roller against the bag to be printed and an inking pad in contact with the roller.

11. A bag rack having in combination 110 therewith a printing device, an upright backing member forming a backing for a stack of flat bags, a front member, a printing roller between the front member and the backing member, and a spring to press the printing roller against the outside of the 115 stack of bags or the like.

12. A bag rack having in combination therewith an upright backing member forming a backing for a stack of flat bags, a printing roller having an inking device co-operative therewith, a frame supporting the printing roller in front of the backing member, and a spring adapted to press the printing roller toward the backing member against the outermost bag of a stack of bags which 120 may be placed therebetween.

In testimony whereof I have signed my name to this specification.
